UNITED STATES PATENT OFFICE

ISIDORE J. HASKEL, OF BROOKLYN, NEW YORK

GRINDING AND POLISHING MACHINE

Application filed November 25, 1930. Serial No. 498,025

This invention relates to a grinding and polishing machine for various materials.

The invention has for its object a machine, by means of which flat and moulded surfaces

5 can be easily produced on stone, metals, glass or other materials. The second object of the invention is the production of a grinding and polishing machine, in which the grinding and polishing appurtenances are actuated at high 10 speed. The third object of the invention is the production of means for a grinding and polishing machine, with which the pressure of the grinding and polishing elements on the material operated upon is automatically 15 indicated. The fourth object of the invention is the production of means to grind the surfaces of the material operated upon, first with small steel balls, then with fine steel powder, and finally to means for polishing 20 the material operated upon. The fifth object of the invention is the production of a grinding and polishing machine in which the débris resulting from its operations is washed away by jets of water, whereby the 25 use of plaster blocks, and the like, for filling in between adjacent stones operated upon is obviated. The sixth object of the invention is the production of a grinding and polishing machine constructed in units spaced from 30 one another, each unit built to protect its moving elements from the debris produced while operating and especially to protect the polishing unit from such debris. The seventh object of the invention is the production of 35 a grinding and polishing machine, in which the units for the various steps of its operation may consist of a plurality of similar appurtenances.

The eighth object of the invention is the 40 production of a grinding and polishing machine, in which the grinding and polishing materials are continuously and automatically fed to the objects operated upon.

The ninth object of the invention is the 45 production of a grinding and polishing machine, that eliminates the usual packing, framing and plastering for the stones or other objects operated upon.

The tenth object of the invention is the 50 production of a grinding and polishing ma-

chine, in which small balls, preferably of steel, are maintained in operative position by magnetic force and are used as grinding elements.

The eleventh object of the invention is the 55 use of carborundum blocks, instead of loose carborundum and water, avoiding the loss of loose carborundum.

The twelfth object of the invention is the 60 use of a constantly fed polishing mixture to the surface of the object operated upon.

The thirteenth object of the invention is the production of a grinding and polishing machine, comprising a plurality of grinding units and one or more polishing units, 65 operating on the objects to be ground and polished, one after the other, so that said objects are fed to the machine at one end and delivered at the other, a finished article.

The fourteenth object of the invention is 70 the production of a grinding and polishing machine, with which smooth and non-wavy surfaces are produced on the objects operated upon, without any special care of the operator, after said objects are properly positioned in the machine.

The fifteenth object of the invention is the production of a grinding and polishing machine, comprising a plurality of grinding and 80 polishing drums, that rotate and at the same time reciprocate in directions parallel to their longitudinal axes, to produce smooth even and non-wavy surfaces on the objects operated upon.

The sixteenth object of the invention is the 85 production of a grinding and polishing machine, provided with ammeters to indicate the pressure of the grinding and polishing appurtenances on the objects operated upon, to avoid the liability of error on the part of 90 the operator, as to the pressure that is produced on the objects operated upon.

The seventeenth object of the invention is the 95 production of a grinding and polishing machine, in which the stones or other objects to be operated upon are located in the feeding end of the machine and leveled with the assistance of plumb marks on the four corners of the objects or stones operated upon, and for which the machine first reduces the 100

high spots and eventually produces smooth and polished surfaces on the objects operated upon.

In the accompanying drawings Fig. 1 represents a side elevation of an exemplification of the grinding and polishing machine, by means of which the steps of the invention are carried out; Fig. 2 shows an enlarged portion of Fig. 1, partly broken away and partly in 10 longitudinal section as on line 2, 2 of Fig. 3; Fig. 3 is a right hand view of Fig. 2 with sections as on the lines 3, 3 and 5, 5 of said Fig. 2; Fig. 4 indicates a top view of Fig. 2 with a section of Fig. 2 on the line 4, 4; Fig. 5 represents a section of Fig. 2 on the line 5, 5; Fig. 6 shows a partial section of Fig. 2 on the line 6, 6; Fig. 7 indicates a section of Fig. 6 on the line 7, 7; Fig. 8 is an enlarged partial section of Fig. 6 on the line 20 8, 8; Fig. 9 shows an enlarged section of Fig. 1 on the line 9, 9; Fig. 10 indicates a section of Fig. 9 on the line 10, 10; Fig. 11 shows a front view of a special grinding segment; Fig. 12 represents an enlarged section of Fig. 25 2 on the line 12, 12; Fig. 13 indicates an enlarged section as on the line 13, 13 of Fig. 3; Fig. 14 shows an enlarged fragmentary portion of Fig. 6; Fig. 15 indicates an enlarged fragmentary portion of Fig. 3; Fig. 16 is 30 a partial top plan view of Fig. 15; Fig. 17 shows another form of the sprocket chains with their appurtenances; Fig. 18 is a partial left hand view of Fig. 17; Fig. 19 shows a fragmentary enlarged portion of one end of Fig. 1 with a modification; Fig. 20 represents an end view of a modified operating or 35 grinding drum; and Fig. 21 shows a partial top view of Fig. 20.

The grinding and polishing machine in this 40 instance is indicated with the foundation comprising the longitudinal walls 20, which on their inner faces have formed therewith the ledges 22 and 23. At their ends the walls 20 have formed therewith the platforms 24 45 with the pillars 25.

To the ledges 22 are secured the angle shaped tracks 30. H beams 31 are supported upon and fastened to the ledges 23. Pairs of journal brackets 33 and 34 are supported 50 upon the platforms 24 of the foundation. A shaft 35 is journaled in the journal brackets 33, and a similar shaft 36 is journaled in the journal brackets 34. The shaft 36 is driven by a motor, not shown, or by other means. 55 The shaft 35 has fastened thereto the pair of sprocket chain wheels 38 and the shaft 36 has fastened thereto the pair of sprocket chain wheels 39. Sprocket chains 40 connect the sprocket chain wheels 38 and 39. 60 Pairs of supplemental links 45 are connected to the sprocket chains 40 and support the pusher bars 47. Pairs of channel irons 48 are fastened to and supported upon the H beams 31 and have formed therein the journal 65 bearings 49. Supporting rollers 50 are in-

dicated with the ball bearings 51 and the axles 52 having the journal ends 53. The journal ends 53 are journaled in the channel irons 48.

Upon the top of the wall 20 of the foundation are located in this instance two grinding units designated in their entireties by the letters A and B and a polishing unit designated in its entirety by the letter C. The unit A is used for the first grinding operation of the machine. The unit B is used for the second grinding operation of said machine and the unit C is used for the third and polishing operation of the machine. The said units A, B and C may be increased in number, providing two or more units A, for the first grinding operation, two or more units B for the second grinding operation and two or more units C for the polishing operation.

Each of said units A, B and C comprises four similar vertical H beams 58 which extend up from the walls 20, of the foundation and are fastened thereto by the foundation bolts 59. Pairs of guides 60 are fastened to the H beams 58. Upon the upper ends of the H beams 58 are supported the similar housings 62, 63, 64 and 65. Each housing comprises the lower cup shaped member having the horizontal walls 66, the depending flanges 67 and the upper flanges 68. A cap 69 is fastened to the lower member of the housing. Journal bearings 70 are formed with each of said housings. To one of the H beams 58 of each unit A, B and C is fastened a bracket 71, which supports the electric motor 72. To the armature shaft of the said motor is fastened the pinion 73. A longitudinal shaft 75 is journaled in the journal bearings 70 of the housings 62 and 63. To the shaft 75 are fastened the bevel gears 76, 77 and the spur gear 79, which latter meshes with the pinion 73. To the housings 62 and 65 are bolted the similar journal brackets 81 and 82. A cross shaft 83 is journaled in the journal brackets 81 and 82. A bevel gear 85 is fastened to one end of the cross shaft 83 and meshes with the bevel gear 76. A second bevel gear 86 is fastened to the other end of the cross shaft 83. Brackets 87 and 88 respectively, similar to 81 and 82 are fastened to the housings 63 and 64, and have journaled therein the second cross shaft 93. On the cross shaft 93 are fastened the bevel gears 94 and 95. The bevel gear 94 meshes with the bevel gear 77. In the journal bearings 70 of each of the housings 64 and 65 is journaled a shaft 96. To one of the shafts 96 is fastened the bevel gear 97 and to the other the bevel gear 98. The bevel gear 97 meshes with the bevel gear 86 and the bevel gear 98 meshes with the bevel gear 95.

To the shaft 75 in each of the housings 62 and 63 (see Figs. 2, 15 and 16) is fastened a worm 99. In each of the housings 62 and 63 is rotatively positioned an interiorly threaded 130

- sleeve 100, the upper end of which bears against the cap 69, and the lower end of which extends through the wall 66. The lower member 101 of a ball bearing race is fastened to the wall 66. The upper member 102 of the ball bearing race is positioned over the member 101. Ball bearings 103 are positioned as usual in said ball bearing members. A worm wheel 104 is fastened to the sleeve 100 and meshes with the worm 99. The upper member 102 of the ball race is fastened to the worm wheel 104. A vertical screw 108 having the shank 109 at its lower end, is in threaded engagement with the threads of the sleeve 100. To each shank 109 is fastened a collar 110. A cross head 115, for details see Fig. 13, coacting with each shank 109, comprises the vertical member 113 with which are formed the horizontal members 117, which latter are in slidable engagement with the shank 109. The horizontal members have formed therewith cavities 119, in which are fastened guide plates 120, which engage the guides 60. A flange 121 is formed with each cross head 115. Feathers 122 are fastened to each shank 109 and slidably engage grooves in the horizontal members 117 of the cross heads. Springs 123 encircle the shank 109 and bear between the collar 110 and the members 117 of the cross head 115. In each of the housings 64 and 65, as already stated, is journaled a shaft 96, which takes the place of the shaft 75 and to which is fastened one of the worms 99. Each of the latter housings is provided with the screw 108 with its appurtenances which coact with its cross head 115.
- To a pair of the flanges 121 of each unit A, B and C is bolted the cross I beam 124. To the I beam 124 are fastened the longitudinal channel irons 128. Tracks 130, with the guide strips 131 are positioned upon and fastened to the cross I beams 124. Each pair of beams 124, with its appurtenances, comprises the lower carriage L of each unit A, B and C.
- The upper carriage, designated in its entirety by the letter U, comprises the cross H beams 132, to which are fastened the longitudinal H beams 133. To the lower faces of the H beams 132 are fastened the shoes 135, which engage and slide upon the guide strips 131, by virtue of which each upper carriage U, with its appurtenances to be described, is slidably supported upon its accompanying lower carriage L.
- To the lower faces of the longitudinal H beams 133 are fastened the pairs of journal brackets 140 having the caps 141, and the pairs of journal brackets 142 having the caps 143. The axial center of the brackets 142 is below the axial center of the brackets 140. Bushings 144 are provided for the journal brackets 140 and 142, which are clamped in place by the caps 141 and 143.
- In each pair of bushings 144 is journaled the drum shaft 145. One of the shafts 145 of each unit A, B and C extends beyond one of its journal brackets and has fastened thereto the elongated pinion 146.
- To each of the shafts 145 of the units A and B is fastened an operating drum designated in its entirety by the letter D (for details see Figs. 6, 7, 8 and 11). Each drum D comprises the pair of hubs 151, from which extend the webs 152, and the latter join with the shell 153. Each of the hubs 151 has a portion 154 reduced in diameter. A ring 155 of electric insulating material is fastened to each of the hubs of the drum.
- An electric conductor ring 156 is fastened to each ring 155. Each of the conductor rings 156 has extending therefrom a terminal 157. A coil 160 has its ends connected to the terminals 157. Brackets 161 fastened to the inner face of the shell 153 secure the coil 160 in place. Notches 165 extend longitudinally into the outer face of the shell 153, and have secured therein the grinding segments 166, which do not extend the full length of the shell 153. A spur gear 170 is fastened to each shell 153 by means of the screws 171. Angle brackets 172 maintain the segments 166 in fixed position to the shell 153, said brackets being fastened to the said segments and to said shell 153.
- A support 175, for details see Fig. 14, extends from each of the caps 141 and 143 and has secured thereto the plug 176 of the electric insulating material. A terminal screw 177 having the nut 178 is supported in each plug 176. A brush holder 179 has formed therewith the brush 180. The brush holder 179 is secured in place by the screw 177 with its nut 178, and the brush 180 bears against the electric conductor ring 156.
- On the top of one of the longitudinal H beams 133 of each unit is located the bracket 184, on which latter is supported the electric motor 185. A second bracket 186 is fastened to the bracket 184.
- A pinion 187 is fastened to the armature shaft of the electric motor 185, and an intermediate pinion 188 is journaled on a pivot 189 extending from the bracket 186. The pinions 187 and 188 mesh with each other, and the latter pinion 188 meshes with the spur gear 170. An ammeter 190 is provided for each electric motor 185.
- A pair of brackets 194 extend from each longitudinal H beam 133 of each unit A and B, and support the hopper 195. At the lower end of each hopper is formed the longitudinal outlet opening 196.
- A coil 197 encircles each of said hoppers 195 and the ends 198 of the coils 197 are connected to a pair of lead wire, not shown, for electric current. Brackets 199 extend from the hopper 195 to hold the coil 197 in place.
- The upper carriage U has extending from one of its H beams 133 the bracket 200, see

Figs. 4 and 5. A link 201 has one end pinned to the bracket 200 by means of the pin 202. The other end of the link 201 is pinned to the triangular shaped link 205, by means of the pin 206.

A bracket 208 is fastened to one of the channel irons 128 of the lower carriage L. The triangular shaped link 205 is pinned to the bracket 208 by means of the pin 209. A shaft 210 is journaled in the bracket 208 and has fastened thereto one end of the arm 211. A link 212 connects the triangular shaped link 205 and the arm 211, by means of the pins 213 and 214. The pin 214 is threaded at one end and is provided with the nut 215, to be enabled to disengage the link 212 from the arm 211. The shaft 210 is supported in a pair of journal brackets 218 and 219 formed with the bracket 208. A worm wheel 225 is fastened to the shaft 210. A second pair of journal bearings 226 are formed with the bracket 208, and have journaled therein the shaft 227, to which is fastened the worm 228 that meshes with the worm wheel 225. At one end of the shaft 227 is fastened the spur gear 230 which meshes with the elongated pinion 146.

To one of the vertical H beams 58 of each of the units A, B and C is fastened the bracket 231, see Figs. 3 and 4, which is on the same level with the bracket 71 of its unit. Eyes 232 extend from the lower face of the brackets 71 and 231 and support the discharge pipe 233 having the perforations 234 in the lower side. One end of each of the pipes 233 is closed with the plug 235.

In the unit C, for details see Figs. 9 and 10, are fastened to its journal brackets 140 and 142, the hollow shafts 239 that have formed therewith the outlet openings 240. A pair of polishing drums each designated in its entirety by the letter P, have each the hubs 241 with the bushings 242. Webs 243 extend from the hubs 241 and support the shell 244. Openings 245 are formed in the shell 244. A spur gear 246 is fastened to the shell 244 by means of the bolts 247. The spur gear 246 meshes with the pinion 188 of its unit C. A felt covering 248 is fastened to the outer surface of each shell 244.

A tank 253 is supported on one of the H beams 133 of the unit C. Piping 254 having the valve 255 extends from the tank 253. Flexible tubes 256 extend from the piping 254 and are provided with the metallic threaded ends 257. The latter are in threaded engagement with the hollow shaft 239.

To operate the machine the lower carriages L and the upper carriages U are located to bring the grinding segments 166 of the operating drums D, one of each pair of which is lower than the other, and the polishing drums P, one of which is lower than the other, in proper position for stones or other material to be operated upon, by means of the electric

motors 72. The motors 72 through the pinions 73 and the spur gears 79 turn the worms 99, which latter turn the worm wheels 104. By this means the sleeves 100 are turned and thereby the vertical screws 108 are moved vertically up or down. With the vertical movements of the shanks 109 of the crews 108 the cross heads 115 are raised or lowered, by means of which the lower carriage L and the upper carriage U of each unit A, B and C with their appurtenances are vertically moved in proper position.

Plates 260 are placed upon the supporting rollers 50 at the entrance end E of the machine. The stones S to be operated upon are then located upon the plates 260 and securely positioned with wedges 266 or blocks 267, and the like, if necessary. The rear end of each stone is placed to abut against one of the push rods 47. The sprocket chains 40 are then driven by rotating the sprocket chain wheels 39, fastened to the shaft 36, by means, not shown, coacting with said shaft. With the movement of the sprocket chains 40, the push rods 47 feed the stones S toward the drums D of the units A and B and the polishing drum P of the unit C. The drums of each unit are turned in opposite directions by the electric motors 185. The hopper 195 of the unit A is charged with small steel grinding balls 270, and the hopper 195 of the unit B is filled with steel powder. Electric current flows through the coils 197 which magnetizes the said balls 270 and the steel powder, so that the said balls and particles of powder will adhere to each other, and each forms a curtain when discharged from their hoppers. The coils 160 in the drums D are electrically energized, which magnetizes the grinding segments 166 to a somewhat greater extent than the steel balls 270 and the particles of steel powder. When the drums D of the unit A turn the segments 166 will pick the balls 270 from its curtain and which will adhere to the outer edges of said segments 166. The steel powder which is discharged from the hopper of the unit B will in the same manner adhere to the outer edges of the segments of the latter unit.

The stones S while being fed to the drums D of the unit A, will have their upper faces brought in contact with the steel balls 270 and the outer edges of the segments 166 of said unit A, by means of which the faces of the stones S are subjected to the first operation of grinding. When the stones S are brought to the unit B, the steel powder which hangs in a curtain from the hopper of said unit B is picked therefrom by the operating segments 166 of the latter unit, by means of which the face of the stone is subjected to the second operation of grinding. While the electric motors 185, of the unit A and B, are turning, the upper carriage U of each unit A and B is slowly moved cross-

110

115

120

125

130

- wise a short distance, by means of the links 212 and their appurtenances, which produces even cuts on the stones. After the stones pass each of the units A and B, the jets of water discharge from the pipes 233, clean the surface of said stones. The stones S are now brought to the unit C, where their surfaces are polished by means of the felt covering 248, in a manner similar to that of the 10 operations of the units A and B. The felt coverings are saturated with a polishing compound contained in the tank 253. The supply of the compound is regulated by the valve 255. The stones S in the unit C are 15 polished by the rotations of the polishing drums P and the compound in the drums is ejected through the openings 245. In the unit C the upper carriage U thereof is also moved crosswise to secure a fine polish to the 20 surfaces of the stones. The stones S are finally washed when leaving the unit C by jets of water discharged from the pipe 233 of said unit. The stones are finally removed at the exit end X of the machine.
- 25 The ammeters 190 measure the strength of the electric current passing through the electric motors 185, and thereby indicate the pressure to which the surfaces of the stones operated upon are subjected.
- 30 The springs 123 of the cross heads 115 with their appurtenances provide flexible means for supporting the upper carriages U and the lower carriages L. By this means when a stone S is encountered with a hard spot 35 and the grinding segments 166, or the polishing drums P, do not efficiently perform their functions, the said carriages of the units are slightly raised to prevent injury to the machine.
- 40 Referring to Fig. 11, if moulded work is to be made with the stones S, instead of the grinding segments 166, the grinding segments 275 having the edges 277 conforming to the moulded work to be produced are used.
- 45 Referring to Figs. 17 and 18, the supporting rollers 50 are again shown with the channel irons 48. The sprocket chains are in this instance indicated at 280, and the alternate links thereof have formed therein an 50 elongated opening 281 for the push bars 47. In this modification the sprocket chain wheels 282, similar to 38 and 39, are large enough in diameter to locate the sprocket chains 280 on a level to bring the push bars 55 47 above the rollers 50. In this modification the supplemental links 45 are not used.
- Referring to Fig. 19, the sprocket chain wheel 39, of which there are two at the exit end of the machine, are fastened to the shaft 60 36. The journal bracket 34 is supported on the platform 24. The sprocket chain in this instance has alternate links 290, which have formed therein cavities. Each of said cavities is formed with the curved end wall 291, 65 the straight end wall 292 and the bottom
- wall 293. The pusher bars 47 are supported in said cavities when functioning in the machine. An inclined platform 295 extends up from the platform 24. When the links having said cavities revolve with the turns of the wheels 39, the pusher bars 47 fall from the said cavities upon the inclined platform 295, as well as the plates 260.
- Referring to Figs. 20 and 21, a grinding drum 300 similar to the drums D is indicated 70 having the rows of detachable carborundum blocks 301, which take the place of the grinding segments 166. The blocks 301 of one row break joints with the blocks of the adjacent rows. A grinding unit similar to A or B may 80 be provided between the units B and C with grinding drums like 300.
- Various modifications of the invention may be made and the present exemplification is to be taken as illustrative and not limitative 85 thereof.
- Having described my invention what I desire to secure by Letters Patent and claim is:
1. In a grinding and polishing machine the combination of a rotating operating drum 90 journaled therein, grinding segments detachably connected to and extending from the drum, means to magnetize said segments and grinding means magnetically carried on the outer edge of each segment.
  2. In a grinding and polishing machine the combination of operating drums journaled in the machine, means to simultaneously turn the drums, grinding segments detachably connected to and extending from 100 each drum, means to magnetize said segments, grinding means carried on the outer edge of each segment by virtue of its magnetism and means to move an object operated upon against said grinding means and segments.
  3. In a grinding and polishing machine the combination of two pairs of operating drums, means to turn the drums, grinding segments extending from each drum, means to magnetize said segments, a hopper having 110 an outlet opening positioned adjacent to each pair of drums, steel balls placed in one of said hoppers, steel powder placed in the other hopper, means to magnetize said steel balls while in their hopper, means to magnetize said steel powder while in its hopper, said steel balls automatically discharged through the opening of their hopper and suspended in the form of an apron therefrom, said steel powder automatically discharged from its hopper and automatically suspended in the form of an apron therefrom, said grinding segments of one pair of drums during their rotation plucking said balls from said curtain of steel balls, and the second pair of drums plucking particles of the steel powder from the other curtain during their rotation, a pair of polishing drums journaled in the machine, means to turn the latter drums, means to feed a polishing mate- 115
  - 120
  - 125
  - 130

rial to the outer surface of each of the latter drums and means to first feed stones to be operated upon against said grinding segments and the steel balls of the first pair of drums, said means then feeding said stones to the segments of the second pair of drums and said steel powder, and said means finally feeding the stones to said polishing drums.

4. In a grinding and polishing machine
- 10 the combination of a pair of grinding units and a polishing unit, each of said units comprising four vertical beams, a screw rotatably connected to each of said beams, means to raise and lower said screws, a cross head
- 15 flexibly connected to each screw, a cross beam connected to each pair of the cross heads of each unit, longitudinal beams connecting said cross beams of each unit, the cross heads of each unit with its beams constituting a
- 20 lower carriage, an upper carriage slideable crosswise supported on each lower carriage, a pair of rotating operating drums one on a level below the other journaled to the upper carriage of two of said units, a pair of
- 25 polishing drums journaled to the upper carriage of the third unit, one polishing drum on a level below the other, a pipe having perforations for the discharge of water supported in each unit, a plurality of rollers positioned between the beams of each unit below its drums, a link sprocket chain on the outer sides of said rollers, pusher bars adapted to detachably connect said chains, means to move said chains and plates adapted to
- 30 35 carry objects to be operated upon located upon said rollers, said pusher bars positioned to bear against the rear portions of said objects operated upon.

5. In a grinding and polishing machine
- 40 the combination of rotating drums journaled therein, grinding means carried by the drums, rotating polishing drums journaled in the machine, rollers journaled in the machine in a plane below and spaced from said drums,
- 45 two pairs of sprocket chain wheels journaled in the machine below said drums, means to rotate a pair of said wheels, sprocket chains comprising pairs of links connecting said sprocket chain wheels, the alternate pairs of
- 50 the links of the sprocket chains having cavities with end walls and a bottom wall, a pusher bar adapted to be supported in the cavities of each alternate pair of the links of one chain and in the corresponding cavities of the links of the other chain, plates supported on said rollers, for supporting objects to be operated upon with one end of each object contacting with one of said pusher bars, said objects fed to and below said
- 55 60 drums with the movement of said sprocket chains, and an inclined platform adjacent to the exit end of said machine to receive said pusher bars and said plates as they drop from the cavities of the sprocket chains at
- 65 the exit end of the machine.

6. In a machine of the character described the combination of a pair of rotating drums, grinding segments extending from each drum, means to magnetize said segments, a hopper having an outlet opening adjacent to said drums, steel balls in said hopper, means to magnetize said balls while in the hopper, said balls discharged through the opening of said hopper and suspended in the form of an apron therefrom, said grinding segments during the rotation of the drums plucking said balls from said apron and means to feed an object to be operated upon against said grinding segments.

Signed at the borough of Brooklyn, city 80 of New York, in the county of Kings and State of New York this 29th day of October A. D. 1930.

ISIDORE J. HASKEL.
